G. ADOLPH RIEDEL, OF PHILADELPHIA, PENNSYLVANIA.

Letters Patent No. 87,294, dated February 23, 1869; antedated February 12, 1869.

IMPROVEMENT IN STEAM-GENERATORS.

The Schedule referred to in these Letters Patent and making part of the same.

To all whom it may concern:

Be it known that I, G. ADOLPH RIEDEL, of the city and county of Philadelphia, and State of Pennsylvania, have invented a new and useful Improvement in Steam-Boilers; and I do hereby declare that the following is a full and exact description thereof, reference being had to the accompanying drawings, and to the letters of reference marked thereon.

The nature of my invention consists of a cast-iron steam-boiler, made in sections of one or more hollow rims, with hollow spokes, as hereinafter described.

In the accompanying drawings, which make a part of this specification—

Figure 1 is an end elevation of the improved boiler, made of three sections, A.

Figure 2 is a vertical section, at the line $x x$ of fig. 1.

Figure 3 is a vertical section of a modified form of the boiler, in which the sections A are placed horizontally.

Figure 4 is a side view of one of the sections A.

Like letters, in all the figures, indicate the same parts.

A A A represent three sections composing the boiler.

The rims B of the sections are represented, in the drawings, of circular form on their periphery, yet I do not confine myself to making them of that form, as they may be of elliptical, or other form, and still answer; and instead of the rims being circular in their cross-sections, they may be corrugated, or they may be composed of a succession of chambers, of globular or other form.

There are hollow spokes C connected with the rims B, or with a plurality of rims in the same plane, if desired.

There are man-holes a in the outer periphery of the rims, which are provided with doors b, that are confined by bolts c, which pass clear through two opposite doors. The doors may, if desired, be confined with short bolts in the usual manner. The man-holes are not only intended for the purpose of cleaning out the boiler, but also for the transmission of light throughout the interior of the same.

For the complete accomplishment of this purpose, I construct the sections with an even number of spokes, so that light may pass clear through. This gives the inspector or workman an opportunity of seeing, from the outside, the exact condition of the boiler. If desired, hollow cross-bars may take the place of the spokes; yet I prefer the former, as they give greater strength to the sections, and cause the light to strike more thoroughly on the interior of the rim.

At the bottom of the sections there are cross-tubes or pipes, e, which form a drum, D, when the sections are connected together.

They are held together by means of the bolts d, or may be secured by means of short bolts, by having flanges on their ends.

D' is a steam-drum, placed above the sections A, and connected therewith by means of the steam-pipes E, made in sections, and connected by means of the couplings F, the inner ends of the short pieces E' being se-

cured into the necks f, on the upper edge of the sections A, and the necks f' of the drum D'.

The drum has a projection, g, whose flange, h, is bolted to the flange k' of the projection g'.

This construction and arrangement of the pipes E give flexibility thereto, to compensate for any variations which may occur by the expansion and contraction of the boiler.

The pipes E may be made of cast-iron, when required, in which case the couplings are dispensed with, the pipes having flanges that are confined together by flanges on the necks f and f' of the sections A and drum D.

The condensed steam is conveyed down from the drum D into the sections A, by means of pipes on the outside, or a vertical opening may extend through the necks g and g' into the sections A.

Said sections have lugs, i, which rest on the ledges j of the walls I I of the furnace, as seen in fig. 2.

They are also constructed with annular ribs k, which nearly touch each other, there being open spaces l between them, to allow for the expansion of the metal. If desired, the ribs k may be dispensed with; but when they are used, there should be doors at the bottom of the sections, to provide for cleaning the latter.

One of the pipes, J, is for the connection of a safety-valve, and the other for the steam-discharge pipe.

The spokes C, or hollow cross-bars, may have ribs running in any direction, to form return-flues.

A check-valve may be set between each contiguous section, in any convenient place, to cut off the communication between the sections, in case of an explosion.

A modified form of the boiler is represented in fig 3, which is a vertical section.

The sections A are confined together by means of bolts m, which pass through the hollow bosses n, which form a continuous tube or pipe.

K is the smoke-pipe.

A face view of the section A is given in fig. 4.

I do not claim anything contained in the patents of Augustus W. Newell, dated December 24, 1867; of George W. Field, dated June 23, 1868; and Thomas S. Clogston, dated June 18, 1867; but

What I claim, is—

1. The arrangement of the hollow rims B and hollow spokes C, with the flexible pipes E, as hereinbefore described.

2. The construction of the annular ribs k, when arranged with the rims B, for the purpose of making return-flues, substantially as described.

3. The arrangement of the man-hole plates b and rods c, with the rims B and hollow spokes C, substantially as herein described.

In testimony that the above is my invention, I have hereunto set my hand and affixed my seal, this 5th day of June, 1868

G. ADOLPH RIEDEL. [L. S.]
